UNITED STATES PATENT OFFICE.

CHARLES S. PORTER, OF HOUSTON, TEXAS.

CONCRETE-WALL MOLD.

1,398,915.

Specification of Letters Patent. Patented Nov. 29, 1921.

Application filed June 11, 1920. Serial No. 388,280.

To all whom it may concern:

Be it known that I, CHARLES S. PORTER, a citizen of the United States, residing at Houston, in the county of Harris and State 5 of Texas, have invented new and useful Improvements in Concrete-Wall Molds, of which the following is a specification.

This invention relates to concrete buildings, particularly to molds therefor, and 10 has for its object the provision of a concrete wall mold which is so constructed as to produce a very strong wall having vertically extending channels which form ribs materially reinforcing the structure.

15 An important object is the provision of a mold of this character which includes the use of nailing strips wedgingly engaged between successive portions of the mold and carrying headed members to be embedded 20 within the plastic material whereby the nailing strips will become a permanent part of the wall and remain associated therewith when the mold is removed, these strips being for the purpose of providing attaching means 25 for the interior trim.

Another object is the provision of a device of this character in which the nailing strips are mortised for the reception of sills for holding the floor joists or the roof rafters, as may be found requisite.

30 A further object is the provision of a mold of this character which includes the use of a plurality of trough-shaped members arranged in spaced relation and adapted to 35 define between them vertically extending ribs which reinforce the wall structure, the nailing strips being carried by the edges of these ribs, other means being provided for preventing caving in of the trough-shaped 40 members when the sections of the mold are secured together.

An additional object is the provision of a mold of this character which will be simple and inexpensive in manufacture, highly efficient in use, durable in service, and a general improvement in the art.

With the above and other objects and advantages in view, the invention consists in the details of construction to be hereinafter 50 more fully described and claimed, and illustrated in the accompanying drawings, in which—

Figure 1 is a perspective view of a portion of the outer mold member looking at the 55 rear side thereof,

Fig. 2 is a perspective view of the inner

and outer sections of the mold in assembled relation,

Fig. 3 is a cross sectional view there- 60

Fig. 4 is a perspective view of a wall formed by my mold and showing the mold removed,

Fig. 5 is a perspective view of one of the trough shaped members constituting a por- 65

tion of the inner mold member,

Fig. 6 is a cross sectional view through the

completed wall, and

Fig. 7 is a perspective view showing the

treatment around doors and windows. 70

Referring more particularly to the drawings, the numeral 10 designates broadly the outer mold member which is formed by a plurality of vertical and transverse bars 11 which in actual practice would be pieces of 75 2 x 4 scantling suitably nailed or secured together and reinforced if necessary, by suitable diagonal brace members, not shown. Upon one side the frame formed by these pieces of 2 x 4 is covered by a sheet or sheets 80 12 of sheet metal, preferably galvanized iron. It will be observed that any suitable number of units constructed in this manner may be connected to form a continuous mold structure.

The inner mold comprises a suitable frame 13 formed of pieces 14 of 2 x 4 scantling of 85 any desired number and arrangement and suitably secured. Disposed against the inner frame 13 are trough-shaped members 15 90 vertically arranged and formed also preferably of galvanized iron and these trough-shaped members are arranged in slightly spaced relation with nailing strips 16 disposed between them and having slightly in- 95 clined edges conformingly engaging the inclined sides of the trough-shaped members and these nailing strips 16 are formed of wood and having extending from them headed fasteners 17 such as nails which have 100 their heads disposed in spaced relation to the strips, as clearly shown in Fig. 3, so that these heads will be embedded within the plastic material poured between the outer and inner molds. Disposed within each 105 trough-shaped member 15 and lying against the inner is a vertically extending strip 18 and against this strip is disposed at intervals, a block 19. The outer and inner frames 10 and 13 are connected at suitable 110 intervals by bolts 20 which pass through these members, through the strips 18,

through the block 19, and also through circular washers 21, formed preferably of concrete, disposed between the sheet 12 and the trough-shaped members 15.

It is of course to be understood that the outer and inner mold members are formed in units adapted to be secured together in juxtaposition to form any length or height of wall, the corners being constructed as found preferable. The outer and inner mold members being arranged in position, the space between them is filled with concrete which is allowed to set. After the concrete is set the outer and inner mold members are removed which will leave the strips 16 secured to the wall designated by the numeral 22 in Fig. 4 and Fig. 6 and it will also leave the concrete washers 21 embedded within the wall. It is of course apparent that the purpose of these washers is merely to space the outer and inner mold members apart. When the molds are properly constructed and arranged it will be apparent that all four walls of a house may be poured at the same time.

Referring particularly to Fig. 7, it will be seen that I have provided several treatments for windows or other openings in the wall. In this form it will be seen that the nailing strips 16 are cut away or recessed, as shown at 23, for the reception of sills 24 adapted to support floor joists or roof rafters, as the case may be. It will also be observed that at the top of the wall I provide a plate or plates 25 which may support roof rafters or beams, if preferred. Another feature is that I provide suitable plates 26 and 27 at the vertical and horizontal edges of any desired opening to be made in the wall so that when the cast is made openings will be defined in the wall.

In the construction of walls I prefer to place between the outer and inner mold members vertical and horizontal reinforcing rods 28 and 29, respectively, which are held in position by any suitable means. When the cement is poured it is of course apparent that these rods will be embedded therein, as

clearly shown in Fig. 4, so as to provide a very strong and durable wall structure.

From the foregoing description and a study of the drawings it will be apparent that I have thus provided a simply constructed and consequently inexpensive mold structure which is readily adapted for connection for forming walls, which is provided with strips to be embedded partially within the molded wall whereby to provide means for securing the interior trim, and which will be a general improvement in the art.

While I have shown and described the preferred embodiment of my invention, it is of course to be understood that I reserve the right to make such changes in the form, construction, and arrangement of parts as will not depart from the spirit of the invention or the scope of the subjoined claim.

Having thus described my invention, I claim:

A cement wall mold comprising outer and inner frames, a plurality of separate vertically disposed trough shaped members disposed with their edges against the outer side of the inner frame with their bright portions in spaced relation to the inner side of the frame and having their sides arranged in spaced relation, vertically extending nailing strips disposed between and serving as spacing means for the trough shaped members, reinforcing bars secured upon the inner faces of the sides of the trough shaped members, horizontally disposed spacing blocks located with each trough shaped member and engaging against said reinforcing bars, spacing members disposed between said spacing blocks and the outermost portion of the trough members, spacing washers disposed between the outermost portions of the trough shaped members and the inner face of the outer frame, and tie bolts passing through both frames, through said spacing washer, the spacing block and the spacing member.

In testimony whereof I affix my signature.

CHARLES S. PORTER.
